C. L. WYKOFF,
EARTH BORING REAMER,
APPLICATION FILED JAN. 19, 1920.

1,365,069.

Patented Jan. 11, 1921.

UNITED STATES PATENT OFFICE.

CHARLES L. WYKOFF, OF MOORLAND, IOWA.

EARTH-BORING REAMER.

1,365,069.

Specification of Letters Patent. Patented Jan. 11, 1921.

Application filed January 19, 1920. Serial No. 352,512.

To all whom it may concern:

Be it known that I, CHARLES L. WYKOFF, a citizen of the United States of America, and resident of Moorland, Webster county,

5 Iowa, have invented a new and useful Earth-Boring Reamer, of which the following is a specification.

The object of this invention is to provide improved means for reaming a hole for a 10 well-casing alternately with forming a hole with a drill or auger.

My invention consists in the construction, arrangement and combination of elements hereinafter set forth, pointed out in the 15 claims and illustrated by the accompanying drawing, in which—

Figures 1 and 2 are elevations of the device at right angles to each other, the bits being shown in position for use. Fig. 3 is a 20 cross-section on the indicated line 3—3 of Fig. 1, certain connecting chains being wholly removed. Fig. 4 is a plan, Fig. 5 a side elevation of a bit employed in the device. Fig. 6 is an elevation of a pivot employed to locate a bit in the device.

In the construction of the device as shown the numeral 10 designates a head of generally cylindrical form, which is formed with a screw 11 at one end adapted to be 25 engaged with a drill-rod (not shown) to use this device interchangeably with a drill-head. The head 10 also is formed with wrench-seats 12, 13 on opposite sides adapted to facilitate engagement of a wrench with 30 said head in an operation of removing or applying the head relative to the drill-rod. The head 10 also is formed with a stem 14 extending from the end thereof opposite to the screw 11, which stem is generally rec- 35 tangular in cross-section and of less trans-verse dimension than the head. Side-bars 15, 16 are mounted on opposite sides of and secured to the stem 14 and said bars extend beyond the outer end of said stem in spaced 40 relation a considerable distance and the outer end portions of said bars converge to mutual contact and are connected by a rivet. Backing blocks 18, 19 are mounted between and secured to the side-bars 15, 16 in spaced 45 relation to each other, and each of said blocks is formed with a notch 20 to provide access to the space between them. Bits 21, 22, alike in form and construction and inter-changeably usable, are mounted transversely 50 of and between the side-bars 15, 16, the

shanks of said bits being overlapped and lying beneath the lower ends of the backing blocks 18, 19 and extending substantially across the side-bars. The outer end portions of the bits 21, 22 are widened relative 60 to the shanks by a flange 23 on each bit and, yet, the width of said outer end portions is slightly less than the space between the side-bars 15, 16 in order that they, under conditions hereinafter explained, may be received 65 between said side-bars. Each bit 21, 22 also is formed with a flange 24 extending upwardly on its outer end and adapted to overlap the lower end of a backing block, 18 or 19. Each bit 21, 22 also is formed with 70 a flange 25 extending downwardly on its outer end, a cutting edge 26 being formed, preferably by forging, on the lower margin of said flange. The cutting edge 26 is sharpened and repaired, after use, preferably by 75 forging. The outer face of each bit 21, 22 lies in two planes forming an obtuse angle between them the uppermost plane 27 having the greater area and providing clearance between the bit and the wall of the 80 reamed hole, and the lowermost plane 28 having the lesser area, providing less clearance in use and straightening the flange 25 for use. The bits 21, 22 are pivoted on studs or pivots 29, 30 (Fig. 6) mounted in the 85 side-bars 15, 16 in laterally-spaced relation, as follows: Each bit is formed with a hole 31 located in the lower rear corner of its shank and said hole is adapted to receive, and journal the shank on, a cylindrical portion 32 of one of the studs 29, 30; each stud being formed with a threaded central portion adapted to be screwed into a seat in a side-bar 15, or 16, to locate the pivot portion 90 between the side bars; and each stud being 95 formed with an angular nut-portion 33 adapted to receive the application of a wrench for seating or unseating of the plug. Thus, either bit may be removed and replaced independent of the other. A stud 34 100 is carried by and extends upwardly from each bit 21, 22 and a chain 35 (one of which is shown in Fig. 1) connects each stud to one of two retractile coil springs 36 between the side bars, the upper ends of said springs being secured properly to the side-bars of the stem 14. Either spring and chain may be flexed laterally within or through a notch 20 for manipulation of their connections in assembling or removing either bit. The nut 110

2

portions 33 of the studs project outwardly from the side-bars 15, 16 and, to protect them from injury in the use of the tool, ribs 37, 38 are formed on the side-bars adjacent to said studs. End portions of the ribs 37, 38 are tapered to the outer surfaces of the side-bars in order that they may offer a minimum of resistance to reciprocation of the tool in a drill-hole. It is the function 10 of the chains 35 and springs 36 to hold the bits in their uppermost positions and in contact with the backing blocks 18, 19, whereby said bits are in expanded relation with each other and project to a maximum degree laterally from the side-bars. In such positions the bits bite and engage the wall of a drill-hole and, in reciprocation of the tool, cut and wear down said wall and enlarge said drill-hole through the operation of the edges 26. The springs 36 permit either bit 20 to yield downwardly in upward movement of the tool in use; and also permit the bits to be contracted by downward movement (the edges 26 passing through arcs) so that the outer end portions thereof are substantially received between the side-bars, thus permitting the tool to enter and pass through a well-casing. In this connection, it will be observed that the edges 26 are received 30 between the side-bars in such manner as to avoid contact with the casing or the joints thereof, the bits being held in contracted relation while in the casing by sliding engagement of the plane faces 27, or the side margins thereof with the inner face of 35 the casing. The backing blocks 18, 19 serve as hammers above and on the bits in use.

The connected and converging end portions of the side-bars 15 and 16, below the bits, serve as a guide to keep the tool relatively straight in, and cause it to follow, the drill-hole, and said end portions may be tapered as desired.

Either plug 29, 30, may be mounted rigidly 45 in its side-bar support, the other being removable, and in that event one bit would be removable after removing its pivot and the other bit would be removable from its pivot after the first bit is removed.

50 I claim as my invention—

1. An earth-boring reamer, comprising a head, side-bars extending from said head, spaced backing blocks between said side-bars and abutting said head, overlapping bits between and pivoted to said side-bars and adapted to be wholly received between them and also adapted to abut said backing blocks, and retractile coil springs acting on said bits and adapted to move and hold them

in extended positions projecting laterally 60 from said side-bars.

2. An earth-boring reamer, comprising a head formed with wrench-seats, a screw and a stem, side-bars overlapping and fixed to said stem and extending therefrom in spaced 65 relation, a backing block between said side-bars, the outer end portions of said side-bars converging and being connected, and reaming devices between and carried by said side-bars and adapted to abut said backing 70 block.

3. In an earth-boring reamer, a head formed with wrench-seats on its sides, a screw on one end and a stem on the other end, side-bars fixed to and extending in 75 spaced relation from said stem, the outer ends of the side-bars being converged and connected, backing blocks between and connected to said side-bars, said backing blocks being spaced apart, and reaming devices 80 between and carried by said side-bars and adapted to abut said backing blocks.

4. In an earth-boring reamer, a head, side-bars secured thereto and extending in spaced relation therefrom, spaced backing 85 blocks between said side-bars, and reaming bits mounted in overlapping relation between and adapted to project from opposite sides of said side-bars, and also adapted to abut said backing blocks, said bits being 90 spring-held in extended relation and adapted to move to positions wholly between said side-bars.

5. In an earth-boring reamer, a head, a stem on said head, side-bars fixed to and extending in spaced relation from said stem, backing blocks between and connected to said side-bars, said backing blocks being spaced apart and formed with notches, reaming devices between and carried by said 100 side-bars and adapted to abut said backing blocks, retractile coil springs mounted between said side-bars adjacent the notches of said backing blocks, and flexible connections between said springs and the respective 105 reaming devices.

6. In an earth-boring reamer, spaced members, bits mounted in overlapping relation between said members and separately pivoted thereto, and retractile coil springs 110 secured to said members and to said bits whereby said bits are separately spring-held in one direction.

Signed at Moorland, in the county of Webster and State of Iowa, this 16th day 115 of December, 1919.

CHARLES L. WYKOFF.
